Primary Examiner — Leah Macchiarolo*Assistant Examiner* — Alexandria Dubus(74) *Attorney, Agent, or Firm* — QuickPatents; Kevin Prince(57) **CLAIM**

The ornamental design for a helmet bag, as shown and described.

DESCRIPTION

FIG. 1 is a top perspective view of a helmet bag in a closed configuration, showing my new design;

FIG. 2 is a top perspective view in an open configuration thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in the figures depict stitching, and do form part of the claimed design.

1 Claim, 8 Drawing Sheets(56)
